UNITED STATES PATENT OFFICE

JOHN POTTS, OF CHICAGO, ILLINOIS, ASSIGNOR TO WILSON-JONES COMPANY, OF CHICAGO, ILLINOIS, A CORPORATION OF MASSACHUSETTS

LOOSE LEAF BINDER

Application filed January 2, 1930. Serial No. 417,878.

This invention relates to a loose leaf binder and concerns itself more directly with a metal hinge for hinging the impaling posts to the cover.

5 It is an object of this invention to provide a hinge rod for the purpose stated that has a limited longitudinal movement whereby the hinge member cannot be withdrawn from the covers and is susceptible of a movement 10 that is not much more than sufficient for unlatching the impaling posts.

The invention comprises the novel structure and combination of parts hereinafter described and more particularly pointed out 15 and defined in the appended claims.

In the accompanying drawing which illustrates a preferred form of this invention and in which similar reference numerals refer to similar features in the different views:

20 Figure 1 is a perspective view of a loose leaf binder involving this invention.

Figure 2 is a fragmentary end elevational view of the same.

Figure 3 is an enlarged interior fragmentary plan view.

Figure 4 is an enlarged fragmentary interior plan view of one of the hinge plates showing parts in section.

This invention is applied to a binder consisting of a cover comprising the side members 1 and a rear member 2 which may be integral with the side portions. A hinge plate 3 is attached to the interior side of, and on the margin of each side member adjacent 35 said back member, and this plate is provided with a coil or tube 4 for receiving the latching member 5. The tubular terminal of each plate 3 is provided with spaced notches or recesses 6 for receiving the ends of the impaling posts 7. The tubular terminal of each plate 3 is also cut away as indicated at 8 for a purpose that will later appear.

The latching member 5 consists of two jointed rods 5a and 5b. The rod 5a has one end pivoted to the rod 5b in one of the recesses 8 as indicated at 9. From the pivot point 9, the rod 5a extends along the inner side of the coil 4 and has an offset portion 5c which extends through the other recess 8 and into the tubular terminal 4 for the

purpose of spanning the adjacent post recess 6.

The rod 5b has an offset portion 5d that extends through the first recess 8 and into the tubular terminal 4 for spanning the intermediate post recess 6. From the pivot point 9, the rod 5b extends along the outer side of the coil 4 to the end of the binder where it is folded over providing a pintle arm 5e that extends into the tubular terminal for spanning the third post recess 6. The folded portion of each latch member is preferably bent inwardly to provide a handle as shown in Figure 2.

In Figure 4, the latching member is shown 65 in retracted position in which the pivoted end 10 of the rod 5a abuts the shoulder 11 forming the near end of the first recess 8. The end 10 and the shoulder 11 serve as coacting stops for limiting the withdrawal of the 70 latch member. When the latch member is longitudinally pushed inwardly, the offset pintle portions 5c, 5d, and 5e will span the recesses 6 and pierce the openings in the impaling posts 7 as is usual in the art.

75 It will be appreciated that according to this invention, it is only possible to withdraw the hinge member a short distance so it cannot become lost or distorted. Besides a better and stronger post pintle can be provided.

I am aware that many changes may be made and numerous details of construction may be varied through a wide range without departing from the principles of this invention, and I do not therefore purpose limiting 85 the patent granted hereon otherwise than necessitated by the prior art.

I claim as my invention:

1. In a loose leaf binder, a cover member, a plate having a notched barrel attached to said cover member, a slidable latching section on said plate and having an offset pintle at one end for entering said barrel, said barrel having a slot forming a shoulder for arresting the other end of said latching section, and another latching section connected to the first section and having pintle portions extending into said barrel.

90 95 100 2. In a loose leaf binder, a cover member, a plate thereon having a notched barrel for

receiving impaling posts, a slidable latching member mounted upon said plate alongside of said barrel and having offset pintles, said barrel having slots for receiving said pintles,
5 said latching member including a pair of jointed sections with the end of one section adapted for engaging the end of a slot for limiting the sliding movement thereof in one direction.

10 3. In a loose leaf binder, a cover member including a plate having a curled margin notched for receiving impaling posts, a latching member mounted upon said cover alongside of said curled margin and having offset
15 pintles, said curled margin having slots thru which said pintles extend, said member and curled margin having coacting parts for limiting the movement of said member for preventing the withdrawal of said pintles from
20 said curled margin.

In testimony whereof I have hereunto subscribed my name at Chicago, Cook County, Illinois.

JOHN POTTS.
